UNITED STATES PATENT OFFICE.

ROLAND A. MELVIN, OF WILMINGTON, DELAWARE.

MEANS FOR PROMOTING COMBUSTION AND ECONOMIZING IN FUEL CONSUMPTION.

Application filed March 18, 1922. Serial No. 544,874.

To all whom it may concern:

Be it known that I, ROLAND A. MELVIN, a citizen of the United States, residing at Wilmington, in the county of New Castle and State of Delaware, have invented new and useful Improvements in Means for Promoting Combustion and Economizing in Fuel Consumption, of which the following is a specification.

10 This invention relates to means for promoting combustion and economizing in fuel consumption and it has more particular reference to what may be more correctly defined as a novel means for effecting the consumption of the unburnt products of combustion arising from a bed of burning fuel and ordinarily carried away as more or less dense smoke. As a concrete instance it is well known locomotive and others boilers 15 when in operation are exceedingly wasteful in the consumption of carbonaceous fuel little more than one-third of the actual products of combustion caused by the burning fuel being thoroughly utilized while the remainder 20 is carried away as waste with the smoke.

Now the primary object of my invention is to provide a novel means whereby a great economy in fuel consumption is effected by 25 the thorough burning up of all gases and carbon that normally escapes out of the smoke stack to the atmosphere.

A further object of my invention is to provide a novel means whereby a locomotive 30 or other fire box is furnished with a constant draft instead of an intermittent one whereby choked flues are eliminated with a consequential increased combustion and resultant higher degree of superheated steam.

40 A still further object attained by my invention is the elimination of back pressure in engine cylinders of locomotives by not using any exhaust steam to produce draft in the fire box and exhausting the same direct to the atmosphere by means of pipes 45 to the top of the boiler and thereby raising the steam to a height that will not obstruct the view of the engine crew.

Another object attained by my invention 50 is the elimination of all possibility for hot air and gases being drawn into a locomotive or other engine cylinders which destroy lubrication and causes carbonizing of the piston packings with a consequential deteriorating effect.

With the foregoing and other objects in

view as will be more apparent from the following description, my invention essentially consists in the novel constructional features, combinations and arrangements of parts 60 hereinafter fully described and more specifically defined by the appended claim.

In the further disclosure of the invention reference is to be had to the accompanying sheets of explanatory drawings constituting 65 a part of this specification and in which like characters of reference designate the same or corresponding parts in all the views.

Figure 1—is a sectional elevation illustrative of the application of one practical 70 embodiment of my invention to an ordinary locomotive, the latter being indicated in dotted outline.

Figure 2—is a front end elevation of the same with the locomotive likewise indicated 75 by dotted outline.

Figure 3—is an enlarged cross sectional elevation of one of the pipes with a steam blower insert therein.

Figure 4—is a sectional elevation illustrative of the application of my invention 80 to a stationary boiler of the return tube type; and,

Figure 5—is a front end elevation of the same. 85

Referring more particularly to the views and specifically to Figures 1 to 3 inclusive of the accompanying drawings the numeral 6 indicates by dotted outline a locomotive of the "Decapod" type, 7 the firebox and 8 the 90 ashbox therefor, said parts forming no part of this invention and being merely referred to for a clearer understanding of my novel means for promoting combustion and economizing in fuel consumption. 95

According to this invention I mount longitudinally of and above the locomotive 6 one or more pipes 9 of substantial diameter; said pipe or pipes 9 entering a stack 10 at the forward part of the locomotive, and 100 said stack entering the smoke box 11 for about one-third to one-half of the latter's diameter. Or, in other words, the lower end of said stack 10 extends into the smoke box 11 from the upper part thereof and it is—or 105 may be—slightly flared at its lower end 12 as shown in Figure 1.

Securely fitted into the lower part of the aforesaid stack 10 is a bushing or collar 13 the inner diameter whereof is of a dimension to restrict the outlet from and aid in increasing the induced draft through the 110

firebox 7, smoke tubes 14 and smoke box 11. Seated upon the aforesaid bushing or collar 13 is an annular coil or pipe 15 having perforations 16 about its inner peripheral surface. This annular coil or pipe 15 serves in use as a steam blower in that it is connected in any appropriate manner with a source of live steam on the locomotive whereby a constant draft is maintained.

10 Appropriately mounted in the stack 10 above the steam blower 15 is a fan or turbine blower 17 conveniently driven in any of the well known ways by an electric or other motor 18 mounted on the top of the boiler 19. The stack 10 is upwardly extended above the pipe 9 and it is provided with butterfly dampers 20, 21 for purposes later on explained. The rear or cab end of the longitudinal pipe 9 is elbowed at 22 into the upper front of the firebox 7 and it is also provided adjacent said elbow portion 22 with a short stack or atmospheric outlet 23 under the control of a butterfly damper 24. Extending obliquely downwards from the underside of the longitudinal pipe 9 I provide one or more pipes 25 that connect into the ashbox 8, said pipe or pipes 25 being under the control of butterfly dampers 26. 27, 28 are also butterfly dampers respectively fitted in the pipe 9 to the rear of the inlet end of the pipe or pipes 25, and near the outlet end of the elbow portion 22 where it enters the firebox 7. The steam blower 15 may have communication through the branch pipe 15' with the steam chest of the locomotive.

40 In order to carry away the exhaust steam from the cylinders 29 I preferably employ a saddle pipe 30 seating over the smoke box 11 and having an atmospheric outlet 31 whereby said exhaust steam is not permitted to commingle with the products of combustion or smoke as is the prevailing practice at present.

45 Referring now more specifically to Figures 4 and 5 which illustrate the application of my invention to a stationary boiler 32 having three fireboxes 33, it will be noted that I provide each said firebox with a vertical pipe 34 of elbowed formation, the centre one being upwardly extended at 35 to provide an atmospheric outlet under the control of a damper 36 whereas the side pipes 34 are elbowed into the centre one at their upper ends, and each of said pipes 34 is provided with a control damper 37. Extending downwardly from the atmospheric outlet 35 in the rear of the centre pipe 34 is a main pipe 38 in which is fitted the aforementioned bushing or collar 13, steam blower 15, and fan or turbine blower 17, the latter being operated by a motor 18 as hereinbefore described. The connections from the lower ends of the elbowed pipes 34 into the ashboxes are designated by the numeral 39,

and it will be noted in this instance that said pipes are of elbow pattern so as to leave free space for the opening and closing of the firebox doors 40. The dampers for the ashbox pipes are designated by the 70 numeral 41.

75 From the foregoing description the operation of my novel means for promoting combustion and economizing in fuel consumption will be readily understood by those acquainted with the art to which this invention appertains, but in order to clarify the same it may be well to here state that under normal conditions the locomotive installation is operated as follows:—The fan or turbine blower 17 is set in motion and live steam turned on to the steam blower 15 whilst the dampers 20, 24 and 26 are closed, and the dampers 21, 27 and 28 are opened. Thus it will be easily understood that a 80 constant draft is established from the smoke box 11 to the firebox 7 through the main pipe 9 and elbowed end or ends 22 whereby the unburnt products of combustion passing through the smoke tubes 14 will be circulated back to the bed of burning fuel with a requisite amount of live steam and be thoroughly burnt up or consumed without the creation of any smoke.

85 When it is desired that the products of combustion of a draft should be circulated through the firebox 7 it will be perfectly obvious that the dampers 20, 27 will be closed while the damper 2 will be opened, which will result in a complete circulation 90 of the unburnt products of combustion through the ashbox 8 to the firebox 7. On the other hand, when it is found that there is too great a production of carbon dioxide the engineer or fireman will open the dampers 20, 24 for a few seconds which will allow the accumulation of said gas to promptly escape.

100 Still further it is to be noted that when the device is to be run under natural draft 110 the damper 21 may be closed and the damper 20 opened.

115 From the foregoing description the operation of the various dampers with respect to the modified form illustrated by Figures 4 and 5 will be clearly understood without further explanation or description, and whilst I have described and shown preferred embodiments of my invention the right is hereby reserved to make such changes and modifications as fairly lie within the scope 120 of the appended claim.

125 Having described my invention, what I claim as new and desire to secure by Letters Patent is:

130 The combination with a boiler structure including a fire-box, ash box, smoke box, and a smoke outlet stack for atmospherical communication, a branch pipe communicating with said outlet stack and having communi-

cation with the interior of said fire-box, a second branch pipe formed on said first named branch pipe and having communication with said ash box, a relatively short branch pipe having communication with said first named branch pipe and having atmospheric communication, and valves arranged one in each of said branch pipes

and one in said stack and other valves arranged in said first named branch pipe whereby either the second mentioned or relatively short branch pipe may be cut off from active communication with the major portion of the first named branch pipe.

In testimony whereof I affix my signature.

ROLAND A. MELVIN.
